METHOD OF MANUFACTURING
INSULATING SLEEVES

Olof Einar Vilén and Torsten Gunnar Bergnéhr,
Stockholm, Sweden, assignors, by mesne assignments,
to Aktiebolaget Arki, Stockholm,
Sweden, a company of Sweden

Application July 21, 1932, Serial No. 623,694
In Sweden March 13, 1931

1 Claim. (Cl. 154—28)

The present invention relates to a method of manufacturing insulating sleeves of an insulating sheet or quilt of the kind which consists of a layer or body of sea-grass, particularly dried eel grass, or the like, interposed between external layers or sheets of paper or the like, and the invention has for its purpose to produce an inexpensive and efficient pipe covering or insulation which shall have the same excellent insulating property as the said material.

The method according to the invention is principally characterized by that the external layer of a strip of such insulating quilt is moistened, at least on one side of the strip, after which the strip is rolled or coiled, for instance on a rod or axle, to an approximately cylindrical shape and is retained in such coiled shape, for instance by means of a surrounding metal sleeve or the like, while said coil is dried by the application of heat, after which the coiled strip is removed from the metal sleeve. The moistening of the external layer of the strip of quilt may suitably be effected by applying to the same a sheet, or several sheets, of paper, fabric, or the like, coated with a suitable paste or glue, or moistened in other manner, and said sheet of paper may also suitably be folded over the opposite edges of the strip.

Thus, when carrying out the method according to the invention, a strip of a suitable width is cut from an insulating quilt of the above-mentioned kind, after which the external paper layer of the strip is to be moistened, at least on one side thereof, which may be effected by direct application of water.

Afterwards this strip is to be rolled or coiled to an approximately cylindrical shape. However, since such a strip cut from a piece of quilt is generally open at both edges, so that the body of insulating material, the eel grass, interposed between the two external paper layers, might easily be pressed out at the edges of the strip, when coiling the same, it is advantageous first to seal said edges, which may suitably be effected by placing the cut strip of quilt on a sheet, or several sheets, of paper, fabric, or the like, after which said sheet is folded around the opposite longitudinal edges of the strip. Said sheet of paper or the like may be coated, for instance, with a suitable paste or glue, whereby, when the strip of quilt is placed on the same, the external layer

of the strip becomes simultaneously moistened, or the sheet of paper may be moistened in some other manner and, when applied to the strip of quilt and folded around the edges of the same, the sheet of paper may be fastened to the strip by means of staples or in other suitable manner, or said sheet of paper may be moistened after it has been fastened to the strip of quilt.

When the external layer of the strip of quilt has been moistened in one manner or other, as above stated, the strip of quilt is rolled or coiled by hand or by means of a suitable machine, for instance around a rod or around an axle or mandrel, so that said strip obtains an approximately cylindrical shape, and when so coiled it is inserted in a cylinder or sleeve of metal or the like.

The accompanying drawing shows a cross section of the strip of quilt coiled around the rod or axle and inserted in the metal cylinder. 1 denotes the strip of quilt having external paper layers 2, 2, and 3 is the surrounding sheet of paper folded over the edges of the strip. The strip is coiled around the rod or axle 6 so that the edges of the strip overlap, and the strip is placed in the metal cylinder 7. Said cylinder with the coiled insulating strip therein is then placed in a drying chamber to be dried. During the drying the moisture evaporates from the external layer of the strip and from the surrounding sheet of paper, and the coiled strip of quilt will therefore retain the cylindrical shape which it has obtained during the coiling. When the drying is completed, the cylinder is taken out of the drying chamber and the coiled insulating sleeve is removed from the same.

By the treatment above described the result is attained, as already stated, that the coiled strip of quilt retains the shape illustrated in the drawing. The insulating sleeve thus produced is elastic or resilient, however, so that after its overlapping edges have been separated and the sleeve has been passed over and placed around a pipe or the like, the sleeve will resume its closed shape so that the edges will again overlap.

If a bent tube is to be insulated, a suitable number of more or less V-shaped cuts are made in the insulating sleeve in that side of the same which will have the smallest radius of curvature when the sleeve has been placed around the pipe.

We claim:

50

The method of manufacturing insulating sleeves of an insulating material or quilt of the kind which normally has a plane sheet-like shape and which consists of a layer or body of sea-grass or the like interposed between external layers of paper or the like which are joined and held together by stitching through said external and intermediate layers, which consists in moistening the outer surface only of the external layer at least on one side of a strip of such insulating

quilt by applying to the same a sheet of paper, fabric or the like coated with an adhesive, folding said sheet of paper or the like over the edges of said strip, coiling said strip to an approximately cylindrical shape, and drying said coiled strip by the application of heat while retaining its coiled shape. 5

OLOF EINAR VILÉN.
